CLAIM

The ornamental design for a cosmetics brush, substantially as shown and described.

DESCRIPTION

FIG. 1 is a perspective view of a cosmetics brush showing my new design;

FIG. 2 is a front elevation view of FIG. 1, the rear being a mirror image;

FIG. 3 is a right side elevation view of FIG. 1, the left side being a mirror image;

FIG. 4 is a top plan view of FIG. 1;

FIG. 5 is a bottom plan view of FIG. 1;

FIG. 6 is a perspective view of a second embodiment thereof;

FIG. 7 is a front elevation view of FIG. 6, the rear being a mirror image;

FIG. 8 is a right side elevation view of FIG. 6, the left side being a mirror image;

FIG. 9 is a top plan view of FIG. 6; and,

FIG. 10 is a bottom plan view of FIG. 6.

The broken lines in FIGS. 1 and 6 illustrate portions of the cosmetics brush that form no part of the claimed invention.

1 Claim, 6 Drawing Sheets
